UNITED STATES PATENT OFFICE

LOUIS SIMON FRAPPIER AND EWALD BOECKING, OF BROOKLYN, NEW YORK, ASSIGNEES
TO INTERNATIONAL PROJECTOR CORPORATION, OF NEW YORK, N. Y., A CORPOR-
ATION OF DELAWARE

LUBRICATING SYSTEM FOR PROJECTION MACHINES

Original application filed August 31, 1928, Serial No. 303,162. Divided and this application filed November 30, 1928. Serial No. 322,786.

This invention relates to a projection head for motion picture projection machines, and more particularly, to a method and means for applying lubricant to the mechanism includ- 5 ed therein.

This application is a division of our co-pending application, Serial No. 303,162, filed August 31, 1928, for improvements in pro- jection machines.

10 An object of the present invention is to insure an even lubrication to the various moving parts of the projection head.

Another object is to provide a continuous oil supply which is capable of applying a 15 measured quantity of lubricant to the machine over a considerable period of time.

A further object is to provide an oiling mechanism which is capable of operating irrespective of the angular position of the pro- 20 jection head.

The above objects and others which will be apparent as the nature of the invention is disclosed are accomplished by dividing the projection head into a plurality of chambers, 25 each of which contains certain of the rotating gears and driving mechanism. A quantity of lubricant is maintained in each chamber sufficient to contact with the lower rotating gear, which thereupon applies said oil to the 30 remainder of the rotating mechanism by a system involving a combination of pressure and splash.

The invention also consists in certain new 35 and original features of construction and combinations of parts hereinafter set forth and claimed.

Although the novel features which are believed to be characteristic of this invention 40 will be particularly pointed out in the claims appended hereto, the invention itself, as to its objects and advantages, the mode of its operation and the manner of its organization may be better understood by referring to the 45 following description taken in connection

with the accompanying drawings forming a part thereof, in which

Fig. 1 is a longitudinal sectional view of a projection head showing the gear chamber and associated apparatus;

Fig. 2 is a transverse sectional view of the upper portion of the projection head; and

Fig. 3 is a transverse sectional view of the lower portion thereof.

Like reference characters denote like parts in the several figures of the drawings.

In the following description and in the claims parts will be identified by specific names for convenience, but they are intended to be as generic in their application to similar parts as the art will permit.

Referring to the drawings more in detail, the projection head is shown as including feed sprockets 10 and 11, by means of which the film is withdrawn from the upper film magazine and applied to the lower film magazine respectively, intermittent sprocket 12, idler sprocket 13 and continuous sprocket 14. The particular form of construction of the sprockets and method of mounting the same on the driving shafts is described in detail in the copending application above named. Only so much thereof as is necessary to an understanding of the oiling device will be set forth herein.

Sprockets 10 and 11 and the driving shafts therefor are of similar construction. Considering sprocket 11 by way of example, it is noted that said sprocket is secured upon rotating sleeve 20 which is driven by gear wheel 21 meshing with a cooperating gear 22 on vertical drive shaft 23. Sleeve 20 is rotatably mounted upon stationary shaft 24 which is provided with bearing surfaces 25 and 26. A portion of sleeve 20 passing through the wall of oil chamber 27 is provided with threads 28 which are adapted to prevent oil from creeping along said shaft into the film chamber and to discharge any oil which is applied thereto into the oil chamber. Shield 29

29 may be employed for preventing direct passage of oil into the film chamber.

5 Sprockets 12 and 14 may be of similar construction, and may be applied to shafts 30 and 31 respectively in any desired manner. Sprocket 12 has been shown by way of example as comprising a central portion 32, which is frictionally secured to shaft 30 and cupped end portions 33 and 34. Oil shield 35 10 is positioned interiorly of cupped portion 33 and prevents oil from discharging onto the surface of said sprocket.

Shaft 30 is rotatably secured in sleeve 37 by means of bearings 38 and 39. Said shaft 15 is secured to star wheel 40 forming a portion of the Geneva driving mechanism of any well known form. Said driving mechanism includes gear wheel 41 which is secured upon shaft 42 and is driven by cooperating gear 20 43. Said gear 43 is mounted upon shaft 44 and is driven by gear 45 which meshes with a cooperating gear on vertical drive shaft 23. Shaft 44 is rotatably mounted in sleeve 46 by means of bearings 47 and 48.

25 Mounted in conjunction with gear 41 are a plurality of fins 50 (Fig. 1), which are adapted to dip in the oil contained in chamber 51 and throw the same in a spray throughout the various parts of said chamber. Oil 30 trough 52 is mounted adjacent gear wheels 43 and 45 and is adapted to catch a portion of this oil and discharge the same onto bearing 48.

35 Idler sprocket 13 is rotatably secured to sleeve 55 which rotates about stationary pin 56. Said pin 56 is drilled by longitudinal bore 57 and transverse bore 58 to receive oil from chamber 51 and apply the same to the rotating surface of sleeve 55. Said sleeve is 40 also provided with oil threads 59 to prevent oil from creeping along the surface thereof. The oil from pulley 13 is discharged through passage 60 into lower oil chamber 27.

45 Shaft 31 is mounted for rotation in bearings 65 and 79 and is driven by flexible washer 66 which is secured thereto between oil shields 67 and 68. Said washer is driven from housing 69 forming a part of gear wheel 70 which is driven by a suitable cooperating gear on 50 shaft 23. Oil shields 71 forming a part of said housing are secured adjacent oil shields 67 and 68 for preventing access of oil to washer 66. Said oil shields may be provided with oil threads for preventing creepage of 55 oil along the surface thereof and discharging said oil away from washer 66. Oil tube 75 is provided with an open end 76 which is located adjacent gear wheel 70 in a position to receive oil from said gear wheel and to 60 discharge the same through passage 78 to bearing 65 and through said pipe 75 to bearing 79.

The upper oil chamber 80 includes a centrifugal control mechanism 81 and sleeve 82 for driving sprocket 10. Sleeve 82 is driven

by gear 83 which is mounted thereon and co-operated with driving gear 84 on vertical shaft 23. Centrifugal device 81 is also driven from gear 84 through suitable cooperating gears (not shown). Sleeve 82 is similar in construction to sleeve 20 and may be provided with oil threads 85 to prevent oil from creeping thereabout into the film chamber.

Oiling system.

75 The upper oil chamber 80 is lubricated by a bath of oil which is maintained therein at a level above the bottom of gear wheel 83. In rotating said gear wheel picks up oil from said bath, applies the same directly to gear 84 and rotates with sufficient force to distribute the same throughout said chamber onto centrifugal device 81. An oil scraper 86 (Fig. 1) may be positioned adjacent the gear wheel 83 for preventing an excess of 85 oil from being carried thereby.

In the second oil chamber 51 oil is maintained at a level sufficiently high to contact with fins 50 on gear 41. The oil is then thrown by said fins in the form of a fine spray throughout said oil chamber thereby oiling the various gears in the upper portion thereof. Oil is thus applied through oil hole 90 to bearings 38 and 39 and passing over bearing 39 is discharged by oil shield 35 through bore 91 to shaft 42, thence through bore 92 is returned to oil chamber 51. The fine spray also lubricates the Geneva gears. A portion of the spray is caught in trough 52 and applied through oil hole 93 to bearings 47 and 48 of shaft 44.

100 Sprocket 13 is oiled through bore 57 which communicates with the oil in chamber 51 and applies the same to the sleeve 58 whence it is discharged through passage 60 into oil chamber 27.

Oil is maintained in chamber 27 at a level above that of the bottom of the gear 21, by which it is picked up and thrown onto gear 70 and throughout the various parts of the 110 oil chamber. Oil which is carried by gear 70 is applied to the open end 76 of pipe 75 and thence discharged through passage 78 to bearing 65 and through pipe 75, bearing 79. Oil from bearing 79 is prevented from 115 contacting with sprocket 14 by means of shields 93 similar in construction to shield 35 described in connection with sprocket 12, thence it is returned through passage 94 to chamber 27. The oil thrown up by gear 120 wheel 21 is applied through oil hole 95 to bearings 25 and 26 on shaft 24, thence it is discharged through oil hole 96.

125 Oil is preferably maintained at the desired levels in chambers 80, 51 and 27 by means of pipes 97, 98 and 99 respectively (Fig. 1) which terminate in said chambers at the required oil level. Said pipes preferably terminate adjacent gears 43, 41 and 21 respectively in order that the proper level of oil 130

will be maintained adjacent said gears irrespective of the angle of inclination of the projection head. This feature is of particular importance as the above mentioned gears are chiefly relied upon to contact with the bath of oil in said chambers and to distribute the oil in the manner above described.

Pipes 97, 98 and 99 may be fed from a closed oil reservoir 100 which is mounted above said projection head and is provided with an opening 101 through which it may be filled as desired. The oil from said reservoir will be discharged through the respective pipes until the oil level in the chambers in which they terminate is at or above the end of said pipes thereby preventing further quantities of air from entering said pipes and from being applied to reservoir 100. Thereafter no flow of oil will take place in said pipes until the oil level in one of the oil chambers falls below the bottom of the supply pipe and again admits air thereto.

For purposes of filling the reservoir 100 it is necessary to remove cap 101 and thereby admit air to said reservoir. Pipes 97, 98 and 99 are preferably sufficiently small to discharge oil at a slow rate, as for example, a few drops per minute. In this case the increase of flow in said pipes during the time consumed in filling reservoir 100 will not be sufficient to affect the system. If desired, however, suitable valves may be employed for cutting off the flow of these pipes when said tank is being filled.

35 It is noted that in the system above described only one application of oil is necessary, namely, in reservoir 100. Oil is applied continuously as desired from said reservoir into the various gear chambers and is
40 applied by a splash system in said gear chambers to the various rotating parts. The mechanism accordingly requires no rigid supervision and may be continuously operated with only such attention as is necessary to
45 maintain oil in reservoir 100.

While certain novel features of the invention have been shown and described and are pointed out in the annexed claims, it will be understood that various omissions, substitutions and changes in the forms and details of the device illustrated and in its operation may be made by those skilled in the art without departing from the spirit of the invention.

55. What is claimed is:

60 1. In a projection head having plurality of vertically displaced oil chambers, a driving shaft extending through said chambers, gear wheels associated therewith, a plurality of gears driven by said gear wheels and means for lubricating said gears comprising an oil bath contacting with a gear wheel in each chamber and means whereby oil is picked up
65 by said last mentioned gear wheel and is ap-

plied to the remainder of the rotating parts in said chambers.

2. In a projection head, an oil chamber, means for lubricating said chamber comprising an oil bath, a gear dipping in said bath, means whereby said gear applies oil directly to adjacent gears and applies a spray of oil throughout said chamber, an oil feed pipe terminating adjacent one of said gears, and means whereby oil is applied thereto from said gear in sufficient quantity for lubrication purposes. 70 75

3. In a projection head, an oil chamber, a pair of rotating shafts therein, a driving shaft therefor, gears associated with each of said shafts and said driving shaft, bearings for said shafts, means for lubricating said bearings and said gears comprising an oil bath in said chamber, a gear on one of said shafts dipping in said bath and applying said oil to the remainder of said gears, an oil pipe for directing oil to one of said bearings, said pipe terminating adjacent one of said gears and having an open end adapted to receive oil therefrom. 90

4. In combination with a projection head, an oil chamber, a driving mechanism therein including a Geneva gear, means for oiling said mechanism including a bath of oil, fins associated with said Geneva gear and dipping in said bath, said fins being adapted to throw said oil throughout the various parts of said chamber, a shaft for driving said Geneva gear, bearings for said shaft and an oil trough for catching oil discharged from said fins and for applying said oil to said bearings. 100 95

5. In combination with a projection head having a pair of oil chambers, an idler pulley located at the lower portion of one of said chambers, an oil bath in said chamber, means for applying oil from said bath to said sprocket and means for discharging oil from said sprocket into the other of said chambers.

6. In combination with a projection head having an oil chamber, means for maintaining a bath of oil in said chamber comprising a closed oil reservoir located above said chamber and a discharge pipe leading from said reservoir and terminating at the required oil level in said chamber. 115

7. In combination with a projection head having a plurality of oil chambers, means for maintaining a bath of oil in each of said chambers comprising a closed oil reservoir located above said chambers, and pipes depending from said reservoir and terminating in said chambers at the level of oil required therein, said pipe serving to discharge oil from said reservoir into said chambers. 120 125

8. In a projection head, a plurality of oil chambers, lubricating means including an oil bath in each of said chambers, elements dipping in said baths, an oil reservoir, and sup- 130

ply pipes from said reservoir terminating in each of said chambers adjacent said elements at the level of the required bath, said pipe serving to maintain the bath at the required level for permitting said gears to dip therein irrespective of the angle of inclination of the projection head.
